UNITED STATES PATENT OFFICE.

ABRAHAM POPKIN, OF NEW YORK, N. Y.

DESIGN FOR A CLOAK.

SPECIFICATION forming part of Design No. 21,828, dated August 30, 1892.

Application filed July 21, 1892. Serial No. 440,825. Term of patent 3½ years.

To all whom it may concern:

Be it known that I, ABRAHAM POPKIN, of New York, in the county and State of New York, have invented and produced a new and original Design for a Cloak, as hereinafter described, and fully shown in the accompanying drawings, in which—

Figure 1 is a quarter view of a cloak having my new design, and Fig. 2 is a back view of said cloak.

The essential characteristics of the said design are the double-breasted front, the V-shaped cuffs, the belt, and the hood, with the interlooped cord, as shown.

In the said drawings, A is the cuff, which has the appearance of being V-shaped.

B is a row of trimming down the front of the cloak on the overlapping edge.

C is the collar, which is shown as being 20
ornamented.

D is the belt having loose ends terminating in ornaments, to which are secured tassels.

E is a cord, which passes through the hood and terminates in tassels.

F is the hood, having fluted edges. 25

G are panels produced in the body of the cloak by the slits H, and I are the projecting shoulders of said cloak.

I claim—

The design for a cloak, substantially as 30
shown.

ABRAHAM POPKIN.
